CLAIM

The ornamental design for a water tank for indoor plant cultivator, as shown and described.

DESCRIPTION

FIG. 1 is a front perspective view of a water tank for indoor plant cultivator showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is another front perspective view showing the state in which the top cover has been opened;

FIG. 8 is an exploded view showing a state in which the upper main body is separated from the lower part;

FIG. 9 is a reference view showing the state the claimed design has been installed in an indoor plant cultivator; and, FIG. 10 is a reference view showing the use status in which the upper main body is separated by sliding from the indoor plant cultivator.

The broken lines depict portions of the water tank for indoor plant cultivator that form no part of the claimed design.
